CONTAINER

Eugene Conti, Mount Vernon, N. Y., assignor, by
mesne assignments, to Herz Cup Company, In-
corporated, New York, N. Y., a corporation of
New York

Application February 27, 1932, Serial No. 595,495

8 Claims. (Cl. 229—21)

This invention relates generally to containers of paper or other suitable material and more particularly to an improved rim structure therefor formed integrally with the sides of the container 5 to provide a strong, stiff and compact rim to strengthen the container and resist collapse thereof when used. The improved rim is smooth and of such a contour as to render the container pleasant and efficient for drinking purposes. 10 Containers provided with this rim are inexpensive to manufacture, may be closely nested and packed in a small space, will cooperate properly with the mechanisms of dispensing machines, and in other respects constitute a distinct advance in the art.

In order to furnish a full understanding of the nature and objects of the invention, an exemplary embodiment thereof in a one piece plaited paper cup will be described in detail with reference to 15 the accompanying drawings, in which:

Fig. 1 is a perspective view of a plaited paper drinking cup provided with the improved rim;

Fig. 2 is an enlarged vertical section taken on the line 2—2 of Fig. 1;

20 Figs. 3 to 9 inclusive constitute a series of line diagrams showing the rim at several stages in its formation and in its preferred final form;

Fig. 10 is an enlarged sectional view showing the preferred rim immediately prior to the final 25 stage of formation, the view including parts of the die which perform the operation; and

Fig. 11 is a view similar to Fig. 10 but showing the position of the die parts and the shape of the rim in the final stage of formation.

30 The present invention provides a rim which is formed partly by folding and partly by pressure shaping and the folding is of such a nature that it imparts an inherent or natural tendency to the rim to maintain the final shape which it is given in the pressure shaping operation. The folding and pressing operations are of such a nature that a considerable amount of material is placed near the center of the width of the rim to form a substantial core to strengthen and 35 stiffen the rim, but at the same time permitting the edges of the rim to be made thin. The final pressure shaping operation compacts the rim, gives it the desired cross-sectional contour, and makes it smooth on both the upper and the 40 lower surfaces. A finished plaited cup 15 with this rim 16 is shown in Fig. 1.

In Fig. 2 the finished rim is shown in greatly enlarged section. It is generally elliptical with the ends pointed. This shape may be designated 45 in geometrical terms as "elliptic-lanceolate"; or

since the inner end is not so thin as the outer end it may be more conveniently designated in common terms as "almond-shaped." The upper side or section 17 of the elliptical rim forms the flare at the upped edge of the cup. The inclination of this flared surface is such that a tangent to the outer end of the upper surface is inclined slightly upward toward the outside. It is not quite horizontal. The upper surface is very smooth, there being no perceptible ridges or 5 folds either longitudinal or circumferential in the rim or in the sides of the cup below the rim. The plait of the cup are, of course, visible but to the touch they are scarcely perceptible. The extreme outer edge 18 of the rim is quite thin. This 10 makes it more attractive, it being well known that a vessel with a thin lip or edge is more attractive and pleasant to the user than one with a thick edge. The rim conforms to the lips of the user 15 in a natural and effective manner.

The lower side or section 19 of the rim extends inward toward the cup. Its edge usually does not touch the cup but in case it should it would strike above the root of the flaring upper section, 20 not along the side wall 20.

The next section 22 is folded back in an upward and outward direction from the inner edge 21 of the lower section of the rim to form a lower core section. It passes upward into the space defined by the converging sections 17 and 19 and 25 is there folded reversely downward and inward from the fold line 23 to form an upper core section 24. The last section especially toward its end 25, i. e., the free edge of the cup, lies against the outer or under surface of the flaring top section 17 of the rim. If, in spite of the heavy pressing operation which it has undergone, the upper core section 24 possesses any resiliency the resulting outward pressure, while it may cause the lower edge of the rim to be moved slightly away 30 from the side wall of the cup, will not be effective to cause appreciable opening up of the rim for the reason that the spreading force originating at the fold line 23, would be applied to the lower section 19 near the outer fold line 18 and 35 the lever action is decreased. Also the lever action of the section 22 about the fold line 21 and of the section 19 about the fold line 18 tending to carry the lower edge of the rim outward in an arc centered at the fold line 18 is rendered 40 ineffective because the material along the fold line 21 has been locked in contracted condition and against expansion by high compression in the 45 shaping operation.

Suitable apparatus for forming this rim con- 50

55

stitutes the subject of another application for Letters Patent wherein said apparatus is fully disclosed. One form of mechanism and method of forming the rim are disclosed and claimed in 5 the copending application, Serial Number 597,209, filed March 7th, 1932. For the purpose of this specification it is sufficient to show in Figs. 3 to 9 the various stages of formation of the rim to indicate one exemplary way in which the rim 10 may be formed. It will of course be understood that these diagrammatic views are drawn to indicate folds which in actual practice are made on circumferential lines near the free edge of the cup which in the present embodiment of the invention is of the well known plaited type. In Fig. 3 the upper section 27 of the cup which is to form the rim has been folded outward from a fold line 28 until the section is approximately horizontal. It is advantageous to fold the entire length of 15 stock which is to form the rim outward from its base in the first operation while the outer edge is unconfined and free to expand circumferentially. If several folds were made progressively inward from the outer edge, the outer fold would 20 lock the material against further free expansion when the subsequent inner folds were made. Such free expansion is required if splitting of the material is to be avoided. In Fig. 4 the outer edge 25 has been turned downward about a second fold line 29 intermediate the radial length of the section 27 to form a second section 30. In Fig. 5 the lower edge 25 of the second section 30 has been folded inward about the second fold line 29 until the section 30 lies parallel with the top 30 section 27. In Fig. 6 the folded edge formed at the juncture of sections 27 and 30 has been folded down about a third fold line 31 intermediate the fold lines 28 and 29 to form an end section 32. In Fig. 7 the entire doubled rim is folded down about 35 a fold line 33 which is spaced slightly from the first fold line. It is to be noted that none of the fold lines are sharp. Consequently if the line of bending is later shifted somewhat, as it is herein, no ridges will be left in the rim where 40 the original fold lines were located.

Figs. 8 and 9 show the final stages of the rim formation. Fig. 8 corresponds to Fig. 7 except that the cup has been removed from the pre-forming or folding mechanism and the doubled 45 sections have spread out somewhat due to the resiliency of the material. Fig. 9 shows in line diagram the finished rim. Here the previous fold lines have been shifted somewhat, some more than others, but their positions will be approximately 50 identified as an aid to an understanding of the final form. In this figure the reference numerals of Fig. 2 are applied to the various parts and with these full lead lines are used. Some of the reference numerals of Figs. 3 to 8 55 are also applied to indicate approximately the amount of shifting and with these dotted lead lines are used. From this it will be seen that the final fold line 21 generally corresponds to the transitory fold line 29; that the final fold line 23 generally corresponds to the transitory fold line 31; and that the final section 24 generally corresponds to the transitory end section 32; but the transitory fold lines 28 and 33 have been obliterated, though if they could be identified they 60 would be found somewhere along the final upper section 17 about in the positions indicated.

Figs. 10 and 11 show the cup and rim at the stages indicated diagrammatically in Figs. 8 and 9 but also include a partial section of the die 65 used for shaping the rim under pressure, and

show the multiple layers of paper as they will appear at most places throughout the rim of a cup formed with overlapping plaits. Here the cup is fitted closely upon a male die 35 which is provided with a rim shaping abutment 36; and a female die 37 which is provided with a shaping recess 38 is moved relative to the male die to fold the rim and press it into final shape. The transitory fold line 31 forms a line of weakness which assists in the reverse folding of the end section 32 in this operation.

It is to be noted that the final operation is performed by an effective upward stroke of the female die while the cup is closely fitted on the male die. This causes the rim to be formed without any appreciable movement of the body of the cup relative to the male die. There is therefore no tendency for the body portion of the cup to buckle and it is finished with a smooth surface throughout the side walls and rim.

From the above description it will be seen that the present rim is strong and rigid since it has considerable width in a radial direction and has a great deal of material packed into the center of the rim. As seen in Fig. 2, there are four superposed sections of material at most places in the rim. This, so far as known, has never been accomplished before in any type of rim. The present rim, therefore, may be contrasted favorably against previously known folded rims which were thin and weak and against rolled rims which were hollow, and after they had become moistened or initially distorted at any point, weak also. The present rim is smooth and of an attractive contour whereas most of the previously proposed rims have been wrinkled and of unattractive contour. The hollow rims in particular were rough because the plaits could not be pressed down without destroying the rim and there were in many types deep folds in the side wall of the cup at the base of the rim produced by the required rim forming operations. The present rim tends permanently to maintain its shape due to judicious controllable folding operations which are performed before the pressure shaping operations are instituted. Many previously known rims have had a pronounced tendency to unfold and it has been necessary to saturate or coat them with adhesives or other substances to inhibit this 50 tendency. Such substances are frequently objectionable in appearance or taste or at least are expensive to apply, so that their use is to be avoided if possible. Furthermore, cups with the present rim will cooperate well with dispensing devices, can be nested and packed within a small space, are relatively inexpensive to manufacture, and in other respects represent a distinct advance in the art.

While one form of rim has been illustrated and described it is to be understood that some departures therefrom are permissible; also that while a plaited paper container is illustrated the rim is not necessarily restricted to this type of container; and finally it is distinctly to be understood that the rim may be formed otherwise than in the manner indicated, the steps of formation and the means for effecting certain steps being given simply as an aid to a visualization of one mode of producing the rim and not in any sense as a limitation upon the container or rim as a final article of manufacture. The invention is only to be limited by the prior art and the scope of the subjoined claims.

I claim:

1. A container formed of paper or other suit- 75

able material, comprising in combination, a bottom, a plaited side wall, and a rim integral with the side wall, said rim being generally elliptical in cross section but with tapered ends and including a curved upper section forming a smooth flared continuation of the side wall, a curved lower section folded abruptly downward and inward from the upper section, a lower core section folded abruptly upward and outward from the lower section into the space between the upper and lower sections and extending near to the fold line therebetween, and an upper core section folded downward and inward from the lower core section and in a reverse direction of rotation from the other folds, the rim being compact throughout and the plaits locked.

2. A container formed of paper or other suitable material comprising in combination, a bottom, a side wall, and a rim, said rim being elliptic-lanceolate in shape and including a curved upper section forming a flared upwardly inclined continuation of the side wall, a curved lower section folded abruptly downward and inward from the upper section, a lower core section folded abruptly upward and outward from the lower section between the upper and lower sections in a direction toward the fold line between these sections and lying against the lower section, and an upper core section folded abruptly downward and inward from the lower core section toward the fold line between the lower section and the lower core section and lying against the upper section.

3. As an article of manufacture, a plaited paper container having a rim comprising two sections folded inward and one section folded outward, one of the inwardly folded sections lying against the under side of the upper portion of the rim which forms a continuation of the side walls of the container, the rim being highly compact, smooth and rigid and standing clear of the side of the cup at its lower edge due to the residual resiliency of the terminal section.

4. A paper container comprising a bottom, plaited side walls and a reinforcing rim formed integrally with the side walls, the upper portion

of the side walls being flared outwardly in a smooth trumpet shape without circumferential lines of wrinkling or folding to constitute the upper layer of a multi-layer rim, said rim being highly compressed to the extent that interior voids are substantially eliminated, the rim in cross-section being elongated along its major axis which is inclined upwardly and outwardly with reference to the longitudinal axis of the container 10 but being thick at the center and having a thin outer edge.

5. A container as set forth in claim 4 further characterized by the fact that the rim, including the top portion of the side walls of the container, comprises four folded edge-connected layers of 15 material.

6. A container as set forth in claim 4 further characterized by the fact that the layers of the rim in a direction from the upper edge of the container toward the free edge of the paper, are 20 progressively slightly shorter than the preceding layer but long enough to fill substantially all the space within the rim.

7. A container as set forth in claim 4 characterized by the fact that the rim is formed of 25 four edge-connected layers of material, all of the layers except the terminal layer being folded in one direction of rotation and the terminal layer being folded in the reverse direction of rotation so as to lie against the under surface of the 30 upper layer of the rim.

8. A paper container comprising a bottom, plaited side walls and a reinforcing rim formed integrally with the side walls, the rim, including the top portion of the side walls, containing four edge-connected layers of material and each layer containing three thicknesses of paper throughout substantially its entire extent, said layers being approximately flat, lying directly against each other and being of sufficient length to cover the surfaces of the adjoining layers to form a rim which is substantially without voids, said rim being pressure set to lock the creases between the layers and compress the material.

EUGENE CONTI. 45
